CLAIM

The ornamental design for a case, as shown and described.

DESCRIPTION

FIG. 1 is a top plan view of a case showing our new design. The case is shown in an open position;

FIG. 2 is another top plan view thereof with the unclaimed flap in a closed position;

FIG. 3 is a rear view thereof; and,

FIG. 4 is a front perspective view thereof showing the case in a closed position;

The broken lines showing a portion of the case are for the purposes of illustrating environment and form no part of the claimed design.

1 Claim, 2 Drawing Sheets

FIG. 2

FIG. 1

FIG. 4

FIG. 3

UNITED STATES PATENT AND TRADEMARK OFFICE
CERTIFICATE OF CORRECTION

PATENT NO. : D658,880 S
APPLICATION NO. : 29/404059
DATED : May 8, 2012
INVENTOR(S) : Jody Akana et al.

Page 1 of 3

It is certified that error appears in the above-identified patent and that said Letters Patent is hereby corrected as shown below:

Title page, showing Fig. 1 should be deleted and substitute therefor the title page as shown on the attached page.

Drawings:

Fig. 1 should be deleted and replaced with Fig. 1 shown on the attached page.

Signed and Sealed this
Thirtieth Day of April, 2013

Teresa Stanek Rea
Acting Director of the United States Patent and Trademark Office
